UNITED STATES PATENT OFFICE.

ALBRECHT WAGNER, OF BERLIN, GERMANY.

ADJUSTING DEVICE FOR ROTARY GRINDING-MACHINES.

1,035,925.

Specification of Letters Patent. Patented Aug. 20, 1912.

Application filed December 29, 1911. Serial No. 668,509.

To all whom it may concern:

Be it known that I, ALBRECHT WAGNER, engineer, residing at Ufmanstrasse 2, Berlin, N. W., Germany, have invented certain new and useful Improvements in or Relating to Adjusting Devices for Rotary Grinding-Machines, of which the following is a specification.

This invention relates to adjusting devices for rotary grinding machines or devices for moving the grinding wheel or disk, or more strictly speaking its support away from or up to the blank or work in the machine. Hitherto such devices have been actuated by the reciprocating of the work slide or operating table but this arrangement possesses the disadvantage that as soon as the mechanism for moving the slide or table is thrown out of operation as is, for instance, necessary in connection with surface-grinding or the like, an automatic adjustment or setting of the grinding disk or wheel cannot be effected.

The present invention has for its object to overcome the above disadvantage and it consists in adapting the adjusting device to be also operated, when required, by the driving gear of the machine.

The invention also comprises other details and arrangements hereinafter more particularly referred to.

The accompanying drawings illustrate one mode of carrying out the invention.

Figure 1 is a side elevation showing one convenient form of apparatus constructed in accordance with the invention. Figs. 2 and 3 are respectively front elevations showing a portion of the driving mechanism in two different positions.

In carrying the invention into effect in one convenient manner, the grinding wheel or disk 1 is arranged upon a support 2 which is reciprocated in a known manner through a spindle 3 adapted to be operated by means of a gear wheel 4 which is intermittently rotated through the medium of a pawl 5. In the known arrangement the feeding or operating device or pawl for the gear wheel 4 is intermittently operated by the to-and-fro movement of the table, said operation being effected in the following manner:—The table or slide 6 carrying the work is provided with a rack 7 which is adapted to be driven by a gear wheel 10 through the medium of the gear wheels 8 and 9. The gear wheel 10 is connected to a bevel wheel 11 which engages

with the bevel wheels 12 and 13 loosely mounted upon the shaft 14 which is connected to the main driving mechanism of the machine. A coupling or clutch 15 mounted upon the shaft 14 is arranged between the bevel wheels 12 and 13 and can be reversed or adjusted by means of a lever 16 which is provided with an extension 17 adapted to be alternately engaged by adjustable stops 60 or abutments 18 and 19 mounted upon the operating table or slide 6, the stops causing the arm 16, which is pivoted at 20, to move in such a manner that the clutch 15 is alternately coupled to the gear wheels 12 and 13, by which means the gear wheel 11 is alternately turned to the right or to the left, thus moving the table 6, in the one direction or the other depending upon whether the coupling is in engagement with 70 the wheel 12 or 13. A member 21, preferably curved as shown in the drawings, is secured to the extension 17 and carries in any suitable manner a rack 22 which engages with the wheel 23, the latter being 80 provided with a crank 24 adapted to move up and down a slide or carriage 25 to which a pawl 26 is pivoted the upper end of said pawl engaging with the gear wheel 4. When the extension 17 is caused to swing out by 85 means of the stops 18 and 19 the member 21, and consequently the pawl 26, are moved, thus causing the wheel 4 to move in such a manner that upon a change in the movement of the table or slide the grinding disk or 90 wheel is adjusted or set by a certain amount in relation to the work. Such an arrangement as that above described is, however, known *per se* so that its mode of operation need not here be described in detail. 95

As in the arrangement so far described the adjustment of the driving elements for the setting mechanism of the grinding wheel or disk support depend upon the movement of the table or slide, the grinding wheel or 100 disk support can be automatically adjusted only when the work is moved to and fro past the grinding wheel or disk that is to say, when the work slide is reciprocated. In order to allow of automatic adjustment of 105 the grinding disk or wheel support when the operating table is stationary a worm 27 is arranged upon the shaft 14 and gears with a worm wheel 28 carrying a crank 29 adapted to move a rocking member 31 pivoted 110 about the pin 30. If the grinding wheel or disk support is to be automatically set or

adjusted when the operating table is at a standstill the rack 22 is disconnected from the member 21 and connected up to the member 31 and secured upon the same at 5 any suitable position by means of the screw 32. The remaining driving elements 23, 24, 25, and 26 remain in their original position and the clutch 15 is moved into a central position so that it does not engage either of 10 the wheels 12 or 13, the result of this latter arrangement being that the wheels 11, 9, 8 and consequently the table or slide 6, are at a standstill. When the machine is in operation the member 31 is rocked about its pivotal support 30 through the medium of the shaft 14, worm 27, and gear wheel 28, and in this manner the pawl 26 rotates the gear wheel 4 so that an automatic adjustment or 15 setting of the grinding wheel or disk support results in spite of the fact that the operating table is stationary. If the automatic feed of the grinding wheel or disk support is again to be made dependent upon the reciprocating movement of the operating 20 table, the rack member 22 is merely disconnected from the member 31 and again secured to the member 21 while the clutch 15 is coupled with either of the bevel wheels 12 or 13 whereupon the wheel 4 is moved in 25 the manner above described so that the automatic adjustment of the grinding wheel or disk is secured.

The foregoing description is given by way of example only, and the invention is not to be confined to the details of construction hereinbefore given as such details, and the arrangement of the several parts, may be suitably modified to suit the particular type of grinding machine to which the invention 40 is to be applied.

Having now particularly described and ascertained the nature of my said invention and in what manner the same is to be performed, I declare that what I claim is:—

45 1. In a grinding machine, the combination with the bed or support, a grinding wheel or disk movable laterally on said sup-

port toward and from the work, a work table having a reciprocating motion at right angles to said grinding wheel, driving gear 50 for operating said work table, and mechanism for adjusting said grinding wheel in relation to the work, operable either from the reciprocating work table or from the driving gear independently of the work table, substantially as described.

2. In combination in a grinding machine, a work table having reciprocating movement, a grinding wheel, driving means for the work table, means for adjusting the 60 grinding wheel in a direction transversely of the work table and an operating connection for said adjusting means operable either from the reciprocating carriage or the driving gear, with means for connecting the 65 same with either of said parts, substantially as described.

3. In combination in a grinding machine, driving means, a work holding table, means for reciprocating same, a grinding wheel, 70 a rack bearing arm, mechanism operated thereby to adjust said grinding wheel in relation to the work, means for operating said rack by the reciprocating of the work table, and means for operating the rack from the 75 driving means of the machine independently of the said work table or slide, substantially as described.

4. In combination in a grinding machine, driving means for same, a reciprocating 80 work holding table, a grinding wheel, a rack bearing arm or member, means operated thereby to adjust said grinding wheel in relation to the work, said rack bearing arm being shiftable to be operated either from 85 the work table or by said driving means, substantially as described.

In testimony whereof I affix my signature in presence of two witnesses.

ALBRECHT WAGNER.
